UNITED STATES PATENT OFFICE.

ISAAC G. WATERMAN, OF SANTA BARBARA, CALIFORNIA.

ELECTROMAGNETIC VALVE.

No. 802,955.

Specification of Letters Patent.

Patented Oct. 24, 1905.

Application filed January 12, 1904. Serial No. 188,786.

To all whom it may concern:

Be it known that I, ISAAC G. WATERMAN, a citizen of the United States, residing at Santa Barbara, in the county of Santa Barbara and State of California, have invented new and useful Improvements in Electromagnetic Valves, of which the following is a specification.

This invention relates to electromagnetic valves, and more particularly to waste-valves.

10 The present invention relates to the general type of waste-valve set forth in my copending application, filed September 9, 1903, Serial No. 172,489, embodying the idea of using a single solenoid or coil around the waste-pipe 15 of any receptacle, such as a lavatory or bathtub, and a spring-pressed armature slideable in or on the pipe and controlled by the solenoid, a spring-seated waste-valve, a cam co-operating with the waste-valve, and a pawl 20 and ratchet-wheel for operating the cam; but the improvements embodied in the present invention are adaptable for use not only in connection with the type of valve of the aforesaid application, but also on the valves claimed 25 in other applications heretofore filed by me, instances of which are my applications, filed July 9, 1903, Serial No. 164,888, and Serial No. 171,215, filed August 29, 1903, and other valve applications executed of even date with 30 the present application.

The object of the present invention is the provision of improvements supplemental to the valve-operating mechanism proper, whereby the valve will always be brought to the exact 35 position to which it should be moved to open the valve to its full extent or to completely close said valve, whether or not the valve-operating member moves its predetermined distance in operation.

40 The invention contemplates the use of novel supplemental means for adjusting the valve on the operation thereof to the proper position, so that if only partly opened or only partly closed by the action of the valve-operating member such incomplete movement of the valve will be completed and the fault rectified automatically.

The invention is set forth in detail herein-after and recited in the appended claims.

50 In the accompanying drawings, Figure 1 is a sectional elevation. Fig. 2, an enlarged view of the invention, partly in section; Fig. 3, a similar view showing the different parts in action and the cam and valve-stem in full lines; and Fig. 4, an exterior view of the pipe-section with the armature and solenoid

in section, showing the cut-out portion of the pipe-section and illustrating a modified form of packing.

A lavatory bowl or basin is shown at 1, 60 having the overflow-channel 2 and valve-seat 3 for waste-valve 4, and 5 is the waste-pipe section, suitably coupled to the basin 1 at 6. The waste-valve stem 7 operates through a stationary cross piece or guide 7' and carries 65 a guide 8, movable with said stem, which is suitably guided in the pipe 5 to prevent it from turning. The waste-valve has a normal tendency to close on account of the interposition of a coil-spring 9 between guide 8 and 70 cross-piece 7', and at the lower end of the stem is a roller 10.

Journalized in the pipe-section 5 transversely is a shaft 11, suitably packed at 12, which has secured thereto a cam-wheel 13, having depressions 14 at the ends of its minor axis and 75 depressions 15 at the ends of its major axis. The roller 10 bears on the cam-wheel and is adapted to snap into and out of the different depressions as the cam-wheel turns to thereby 80 open and close the waste-valve.

The outer face of the pipe-section 5 is cut away at 16, and the shaft 11 is there provided with a rigidly-secured ratchet-wheel 17, whose teeth are arranged in four sets of three teeth 85 each. A spring-pressed pawl 18, pivoted to the pipe-section, prevents backward turning of the ratchet-wheel and valve.

Screwed on the pipe-section 5 is a nut 19, which supports a shell 20, packing 21 being 90 used between the shell and nut, around which is a solenoid 22, held against a shoulder 23 on the pipe-section 5.

Surrounding the shell 20 and slideable thereon is a tubular armature 24, which is pressed in 95 one direction by a coil-spring 25.

In Fig. 4 a modification of the above construction exists in the use of packing 26 and a washer 27, interposed between the spring and the head of the solenoid. The packing 100 21 and 26 deaden the noise of the armature when in operation.

Secured rigidly on the outer end of the cam-wheel shaft 11 is a square nut or member 28.

105 The armature has a cut-out portion 29 in one side, which has the parallel abutments or shoulders 30 and 31 at its upper and lower margins, said shoulders or abutments 30 and 31 being, respectively, adapted to strike against opposite edges of the square nut 28 when the armature is attracted by the solenoid and 110

when pressed back again by the spring 25. Pivoted at 32 to the armature is a pawl 33, having three teeth 34, adapted to engage the nearest set of the teeth on the ratchet-wheel

5 when the armature is attracted by the solenoid. This pawl is pressed into engagement with the ratchet-wheel by a spring 35 on the armature.

The supply of current to the solenoid may 10 be controlled by any suitable switch; but any one of a series of temporary contact-switches set forth in my Patents Nos. 775,016, 775,053, 775,055, dated November 15, 1904, is particularly adapted for this purpose, as the solenoid 15 is designed to actuate the armature on temporary electrical energization. When the solenoid is energized, the armature is attracted thereto, and the pawl turns the ratchet-wheel a quarter-revolution, opening or closing 20 the waste-valve according to the prior position of the latter. When the armature is thus actuated, the shoulder 31 strikes against the nut 28, and if the valve has not been positioned correctly the engagement of the nut 25 and said shoulder causes the valve to be positioned exactly correct. When the armature is returned to normal position by the spring 25, the shoulder 30 strikes the nut 28, and if the valve was not correctly positioned previously 30 by the shoulder 31 the engagement of shoulder 30 and nut 28 properly positions the valve.

It will be understood that I do not limit myself to the use of the valve rectifying or adjusting means in connection with a valve of the type set forth in the present application, as I am well aware that the said valve adjusting or rectifying means can be used in connection with rotary valves of different types 40 and the valves of my application heretofore enumerated herein.

In my application, Serial No. 188,783, I have disclosed a valve operated by a toothed wheel and a toothed actuating member coöperating 45 with said toothed wheel and adapted to play between predetermined limits.

Having thus described my invention, what I claim as new, and desire to secure by Letters Patent, is—

50 1. The combination with a valve, of a movable member for opening and closing the valve which is movable relatively to the valve, and means for automatically adjusting the position of the valve after the completed coöperation of the operating member with the valve if the valve has been improperly opened or closed by the valve-operating member.

2. The combination with a valve, and a rotary member for operating the valve, of a 60 movable valve-operating member coacting with the rotary member aforesaid and movable relatively to the valve, to operate the valve, and means for automatically adjusting or rectifying the position of the rotary member after the completed coöperation of the

operating member with the valve to rectify the position of the valve if the valve has been improperly operated by the valve-operating member.

3. The combination with a valve, and a rotary member for operating the valve, of a movable valve-operating member coacting with the rotary member aforesaid and movable relatively to the valve to operate the valve, and means carried by the valve-operating member and adapted to coact with the rotary member aforesaid after the completed coöperation of the operating member with the valve to rectify the position of the valve if the valve is improperly operated by the valve-operating member.

4. The combination with a valve, of a rotary polygonal member coacting with the valve, a valve-operating member, and a member actuated by the valve-operating member 85 adapted to engage a side of the polygonal member aforesaid and rectify the position of the valve if the valve is improperly operated by the valve-operating member.

5. The combination with a valve, of a rotary polygonal member coacting with the valve, a valve-operating member, and shoulders or abutments on the valve-operating member adapted on the advance and retrograde movements of the valve-operating 95 member to respectively engage the polygonal member aforesaid and rectify or adjust the position of the valve if the valve is improperly operated by the valve-operating member.

6. The combination with a valve, of a movable armature movable relatively to the valve for operating the valve, an electromagnet controlling the armature, and means operated by the armature for automatically adjusting or rectifying the position of the valve after the completed coöperation of the operating member with the valve if the valve has been improperly operated by the armature.

7. The combination with a valve, of a movable armature movable relatively to the valve for operating the valve, when said armature is moved in a given direction, an electromagnet for operating the armature in one direction, means for operating the armature in the other direction, and means operated by the armature for automatically adjusting or rectifying the position of the valve after the completed coöperation of the operating member with the valve if the valve has been improperly operated by the armature.

8. The combination with a valve, of a movable armature movable relatively to the valve for operating the valve when said armature is moved in a given direction, an electromagnet for operating the armature in one direction, a spring for operating the armature in the other direction, and means operated by the armature for automatically adjusting or rectifying the position of the valve after the completed coöperation of the operating mem-

ber with the valve if the valve has been improperly operated by the armature.

9. The combination with a valve, of a rotary member for operating the valve, a polygonal member coöperating with the valve, an armature for operating the rotary member, an electromagnet controlling said armature, and a shoulder on the armature adapted to engage the polygonal member and rectify or adjust the position of the valve if the valve-operating member has improperly operated the valve.

10. The combination with a valve, of a rotary valve - operating member, a polygonal member coöperating with the valve-operating member, an armature for turning the rotary member aforesaid, shoulders on the armature to engage the polygonal member and rectify the position of the valve when the movement of the armature in either direction improperly operates the valve, and an electromagnet for operating the armature.

11. The combination with a valve, of a movable member for opening and closing the valve, said member being movable relatively to the valve, and means supplemental to the member aforesaid for automatically adjusting or rectifying the position of the valve if improperly operated by the movable valve opening and closing member.

12. The combination with a valve and a rotary member for operating the valve, of a movable valve-operating member for opening and closing the valve which is movable relatively to the valve and coacts with the rotary member aforesaid to open and close the valve, and means supplemental to the valve-operating member for automatically adjusting or rectifying the position of the rotary member to rectify the position of the valve if the valve has been improperly operated by the valve-operating member.

13. The combination with a valve, of a movable valve-operating member movable relatively to the valve, and supplemental means carried by the movable valve-operating member and adapted to coact with the valve to rectify the position of the valve if the valve has been improperly operated by said valve-operating member.

14. The combination with a valve, of a movable armature movable relatively to the valve for operating said valve, an electromagnet controlling the armature, and supplemental means operated by the armature for auto-

matically adjusting or rectifying the position of the valve if the valve has been improperly operated by the armature.

15. The combination with a valve, of a movable armature movable relatively to the valve and adapted for operating the valve when moved in a given direction, an electromagnet for operating the armature in one direction, means for operating the armature in the other direction, and supplemental means operated by the armature for automatically adjusting or rectifying the position of the valve if the valve has been improperly operated by the armature.

16. The combination with a valve, of a movable armature movable relatively to the valve and adapted for operating the valve when said armature is moved in a given direction, an electromagnet for operating the armature in one direction, a spring for operating the armature in the other direction, and supplemental means operated by the armature for automatically adjusting or rectifying the position of the valve if the valve has been improperly operated by the armature.

17. The combination with a valve, of a rotary member for operating the valve, a solenoid, an armature slidable in the solenoid and movable relatively to the valve, a spring for projecting the armature from the solenoid, means carried by the armature for operating the rotary member, and supplemental means carried by the armature adapted to automatically adjust or rectify the position of the valve if the valve has been improperly operated by the armature.

18. The combination with a valve, of a ratchet-wheel for operating the valve, a solenoid, an armature slidable in the solenoid and relatively to the valve, a spring for projecting the armature, a pawl carried by the armature adapted to engage the ratchet-wheel and turn it, a polygonal member coöperating with the valve, and a shoulder on the armature which is engageable with the polygonal member to automatically rectify or adjust the valve if the valve has been improperly operated by the armature.

In testimony whereof I have signed my name to this specification in the presence of two subscribing witnesses.
